UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

1,378,998.

Specification of Letters Patent. Patented May 24, 1921.

Application filed August 16, 1919. Serial No. 317,911.

To all whom it may concern:

Be it known that I, GEORGE CLAUSING, a citizen of the United States, and a resident of Portsmouth, county of Scioto, State of Ohio, have invented certain new and useful Improvements in Lasts, of which the following is a specification.

This invention relates to an improvement in lasts, and one of the objects thereof is to produce a simple, strong and practical last which can be broken or flexed to the desired extent so as to facilitate the easy and ready removal of the same from the shoe without marring, breaking or pulling the shoe out of shape. In many lasts a V-cut is provided to permit the necessary flexing or moving of the toe and heel parts of the last relative to each other and according to the present invention a construction is provided which permits this V to be made relatively large or long at the top whereby the heel and toe parts can be moved relatively to each other a comparatively large amount so as to permit an easy and ready removal of the last from the shoe when desired.

In the present construction the toe and heel parts of the last are attached to each other by a link having one end attached to the toe part and the other end attached to the heel part, this link maintaining a spring contained within the toe part under compression, so that the last will be held either in extended or broken position as may be desired, this spring preventing relative displacement of the toe and heel parts so that when the last is broken the transverse bearing with which the last is provided may not drop out.

In Patent No. 1,295,273, dated February 25, 1919, there is shown a last having a toe part and a heel part provided with main bearing members or pins between said parts and about which the parts are adapted to be given a partial rotation and a link pivotally connected at one end to the toe part and at the other end to the heel part, this link cooperating with a spring, one end of which is attached to the toe part and the other end to the heel part for maintaining the two parts of the last in either extended position or broken position as the case may be.

The present invention contemplates the employment of a last construction similar to that just referred to. In the present construction, however, the spring is mounted

wholly within the toe part of the last and maintained under compression by the link referred to at all times.

With a construction such as shown herein the V portion of the last can be made comparatively large and the last parts will be maintained firmly together even when the parts occupy the shortened or broken position relatively to each other. In the accompanying drawing Figure 1 shows in part sectional elevation a last of the character above outlined with parts broken away to show the inner construction thereof, the last in this figure being shown in extended position;

Fig. 2 is a view similar to Fig. 1 with the last in broken position; and

Fig. 3 is a horizontal sectional view taken through Fig. 1, showing in full lines the bearing parts for the last and the link and pins by which the two portions of the last are held to each other.

The last as a whole is designated A and comprises toe and heel parts designated B and C respectively. In the formation of the last these two parts may be made integrally with each other from the same piece of wood and are subsequently separated by sawing along the lines Z—Y, Z'—Y, Y—Y' and Y—X'. From an inspection of Fig. 1, it will be apparent that the V portion Z—Y—Z' has been removed from between the upper portions of the toe and heel parts so that said parts can assume the shortened or broken position shown in Fig. 2. A hole is bored at Y for the reception of a transverse main pivot bearing pin or pins D—D' maintained in position against outward movement by means of shoulders ds, these pins constituting a transverse bearing for the toe and heel parts B and C.

The toe part B of the last is provided with a slot 1 and the heel part is provided with a slot 2 for the reception of a link 3, the rear end of the link being provided with a hole through which passes a pin 4 to maintain this end of the link pivotally connected to the heel part of the last. The forward end of the link is provided with a slot 5 through which passes a pin 6 whereby this end of the link will be secured to the toe part of the last, the slot 5 providing a means for permitting the toe and heel parts B and C respectively of the last to be moved from the position shown in Fig. 1 to that shown in Fig. 2.

From an inspection of Fig. 3 it will be noticed that the link 3 is positioned between the inner ends of the bearing members D and D'. The forward end of the link 3 is 5 provided with a projection 7, which together with a pin or stop 8 passing through the toe portion B of the last serves to maintain a spring 9 under compression at all times.

From an inspection of Fig. 1, it will be 10 observed that when the last is in extended or unbroken position, a line passing through the centers of the pins 6 and 4 falls below the center of the main bearing pins D—D', and inasmuch as the spring 9 with the parts 15 in this position is under compression, the toe and heel parts B and C respectively of the last will be maintained in full extended position and in firm engagement with the main bearing pins D—D'. As the last parts 20 are moved from the unbroken position of Fig. 1 toward the broken position of Fig. 2 the link 3 moves to the left as viewed in Fig. 1, this movement being permitted by the slot 5 in the forward end of the link, 25 but this movement is not sufficient to fully relieve the compression of the spring 9 with the result that with the parts in the position shown in Fig. 2 with the spring 9 still under compression, and a line drawn from 30 center to center of the pins 6 and 4 falling above the center line of the bearing pins D—D', the last parts will be maintained in broken position and in firm engagement with the bearing members D—D'. 35 It will therefore be seen that a last has been provided which can be broken or flexed to the desired extent or maintained in extended position as the case may be and the parts of which last are held together by a 40 link which coöperates with a spring provided in the toe part of the last and which spring being under compression at all times will assist in holding the last parts in either extended or broken position and always 45 maintain the last parts in firm engagement with the bearing members about which the parts are adapted to be rotated.

What I claim is:—

1. A last having a toe part and a heel 50 part provided with a transverse bearing member frictionally held in place therein, a link connecting said toe and heel parts and means coöperating with said link and mounted in one of said parts for maintaining the same in extended position and in 55

broken position and for preventing accidental dislodgment of the transverse bearing.

2. A last having a toe part and a heel part, a transverse bearing member for said parts frictionally sustained thereby, a link connecting said toe and heel parts and means carried by one of said parts coöperating with said link for maintaining the toe and heel parts in extended position and in 60 broken position and preventing bodily displacement of the toe part relatively to the heel part whereby the said bearing member will be sustained against accidental dislodgment.

3. A last having a toe part and a heel part provided with a transverse bearing, a link connected to said toe and heel parts, and a spring maintained under compression by a portion of said link to hold the last 75 parts in extended position and in broken position.

4. A last having a toe part and a heel part provided with a transverse bearing, a link connected to said toe and heel parts, a 80 stop on said toe part, and a spring maintained under compression between said stop and said link to maintain the last parts in extended position and in broken position.

5. A last having a toe part and a heel 85 part provided with a transverse bearing, a link one end of which is connected by a pin to the toe part, and the other end connected to the heel part, the end of the link connected to the toe part being provided with a 90 slot through which the said pin passes, said slotted end of the link being provided with a projection, a stop on said toe part and a spring under compression between said projection and stop to maintain the last parts 95 in extended position and in broken position.

6. A last having a toe part and a heel part provided with a transverse bearing, a link connected to said toe and heel parts, a pin passing through a slot in one end of 100 said link and serving to secure the link to one of said parts, a projection on said link, a stop on one of said parts, and a spring under compression between said projection and said stop to maintain said toe and heel 105 parts in extended and in broken position.

This specification signed this 13th day of August, A. D. 1919.

GEORGE CLAUSING.
